DESIGN FOR A TOY CANNON

Frank J. Curran, Hinsdale, Ill.

Application September 20, 1945, Serial No. 122,215

Term of patent 14 years

(Cl. D34—15)

To all whom it may concern:

Be it known that I, Frank J. Curran, a citizen of the United States, residing in the village of Hinsdale, county of Du Page, State of Illinois, have invented a new, original, and ornamental Design for a Toy Cannon, of which the following is the specification, reference being made to the accompanying drawing, forming a part thereof.

Fig. 1 is a side elevational view of a toy cannon showing my new design;

Fig. 2 is a top plan view taken on the lines 2—2 in Fig. 1 of the drawings; and

Fig. 3 is a front elevational view taken on the lines 3—3 in Fig. 2 of the drawings.

I claim:

The ornamental design for a toy cannon, as shown.

FRANK J. CURRAN.
